UNITED STATES PATENT OFFICE.

JOSEPH HENRY HEARNE, OF SANFORD, NORTH CAROLINA, ASSIGNEE OF ONE-HALF TO
CLAWSON LEE WILLIAMS, OF SANFORD, NORTH CAROLINA.

LOOM-SHUTTLE.

1,264,925.

Specification of Letters Patent.

Patented May 7, 1918.

Application filed February 20, 1917. Serial No. 149,744.

To all whom it may concern:

Be it known that I, JOSEPH HENRY HEARNE, a citizen of the United States, residing at Sanford, in the county of Lee, State of North Carolina, have invented certain new and useful Improvements in Loom-Shuttles, of which the following is a description, reference being had to the accompanying drawings, forming a part hereof.

10 The object of the invention is to provide an attachment, adapted to be handled as a separate article of manufacture for use in connection with loom shuttles of the standard type, and adapted to be applied to the 15 shuttle either when the latter is new or before its use, or after the shuttle has been used and by reason of the wearing of certain wooden parts of the body of the shuttle has become less efficient, to thereby restore 20 the same to its original efficiency.

In the construction of shuttle which may be regarded as the standard type, inasmuch as it is the form most generally used, provision is made to prevent wear of the parts 25 of the bobbin-latch by including a metallic abutment for contact with the head of the latch stem, so that the release of the bobbin by the proper operation of the latch when the bobbin spindle is sprung upward may 30 be insured,—the previously encountered wear upon the wooden body of the shuttle, resulting ultimately in the failure of the latch to properly release the bobbin is prevented. In this usual or standard form of 35 shuttle moreover the heel of the spindle head is adapted as the spindle springs back to its position in alinement with the shuttle body, to come in contact with a stop shoulder forming the terminal of a slot communicating with the cavity of the shuttle and the wearing of this shoulder which being formed in the body of the shuttle is of 40 wood and which wear is due to the impact of the heel of the spindle head, eventuates in 45 permitting the bobbin spindle to swing downward beyond its proper position in alinement with the shuttle body, and the disadvantage of such excessive movement is that the thread on the bobbin is brought into 50 contact with the wall of the cavity in the shuttle body and frequent breakages of the thread result.

Various means have been devised heretofore to correct one or the other of these evils 55 and prolong the life of the shuttle by main-

taining the several parts in their normal and originally adjusted positions, but in most cases these means have involved a reorganization or construction of the shuttle itself or of the spindle head, and it is the object 60 of this invention to provide such protective means, in the form of an attachment, as may be applied, as above noted, to the standard type of shuttle without modification of the construction of any of its parts, whereby the application of the attachment may be made either originally or after protracted use of the shuttle resulting, as indicated, in 65 more or less injury due to the causes named.

Further objects and advantages of the invention will appear in the following description of a preferred embodiment, it being understood that changes in the form, proportion and minor details may be resorted to within the scope of the appended claim 70 75 without departing from the spirit of the invention.

In the drawing,

Figure 1 is a perspective view of a portion of a shuttle showing the mounting of 80 the spindle head therein and the operative arrangement of the attachment with reference thereto.

Fig. 2 is a similar view with the shuttle inverted to more clearly indicate the position 85 of the attachment.

Fig. 3 is a longitudinal sectional view showing in full lines the normal or operative position of the bobbin spindle and in dotted lines the displaced position which the 90 spindle assumes when a bobbin is to be removed or mounted thereon.

Fig. 4 is a detail view in perspective of the attachment showing in dotted lines the relative position of the spindle actuating 95 spring.

Fig. 5 is a plan view of the blank from which the attachment is formed and which may be struck from a flat sheet or plate of metal or other suitable material of any desired gage.

In disclosing the invention, the attachment is shown applied to a shuttle of the ordinary construction consisting of a wooden body 10 having the usual metallic tip 11 and a cavity 12 communicating at the under side of the shuttle with a slot 13, said cavity housing the bobbin spindle 14 of which the head 15 is pivotally mounted in the body by means of a pin 16. The spindle head car- 105 110

ries a bobbin-latch 17 of which the stem 18 is provided with a head 19 for contact with a metal abutment 20 of the usual staple form. Also the head of the spindle is provided with a toe 21 bearing upon a follower 22 forming the terminal of a spindle actuating spring 23 arranged in a spring socket 24, while the heel 25 of said spindle head is adapted either directly or through the terminal guide ear 26 of the bobbin-latch, to contact with a stop shoulder 27 forming the extremity of the slot 13 in the under side of the shuttle body.

With this construction, as above indicated, the wearing of the wooden body of the shuttle by contact of the head of the latch stem is prevented by the metallic abutment staple 20, so that the proper operation of the bobbin latch in order to properly release the bobbin may be effected indefinitely. In order to prevent the wearing of the stop shoulder by the impact therewith of the heel of the spindle head, the attachment embodying the invention and shown in detail in Figs. 4 and 5 may be employed, said attachment being struck from a blank of flat sheet or plate material with a head disk 28, a foot disk 29 and a connecting stem 30. Said head and foot disks are bent into substantially parallel planes extending in opposite directions from the extremities of the stem and as so formed the device can be inserted in the spring socket 24 of the ordinary loom shuttle without substantial modification of the latter so that the foot disk receives the pressure of the spindle actuating spring to prevent wear at that point while the head disk which may, as shown, be of angular form rests upon the stop shoulder 27 to receive the impact of the heel of the bobbin spindle as the latter is snapped back to its position in alinement with the shuttle after having placed a bobbin thereon.

In some instances, it has been found desirable to form in the side wall of the spring socket a shallow groove 31, which may be formed without difficulty by means of a chisel, to receive the stem of the attachment, thereby housing the latter and incidentally reinforcing it transversely, but obviously in the event of any injury to the attachment in the use of the device, another attachment can be applied without material loss of time and without requiring skilled labor.

It will be noted moreover that the proposed mounting of the attachment is effected without in any way obstructing or modifying the form of the cut-away portion 32 of

the body of the shuttle provided to afford clearance for the toe of the spindle head. 60

Moreover if found desirable in practice to avoid the battering of the heel of the spindle head due to protracted use, the attachment or the head disk thereof may be made of a sufficiently soft material to absorb the wear, 65 with the advantage of course that the attachment may be replaced when necessary to preserve the efficiency of the shuttle, such replacement being effected quickly and at a comparatively negligible expense. 70

Moreover a device of the type indicated may be constructed and shipped to the consumer in flat form, thus economizing space, and when about to be inserted, the terminal disks may by means of pliers or other suitable tools be bent into the positions desired, the reduced width of the stem providing for effecting such adjustment with facility. 75

It should be noted also that as the stem of the attachment occupies a position in contact with the lower wall of the spring socket, said wall is exposed through the open upper side of the shuttle cavity for the ready manipulation of a chisel in forming the groove to house or countersink said stem. 80

In addition to the foregoing, it will be noted that as the bobbin spindle is swung from its normal or alined position to the dotted line or discharging and receiving position indicated in Fig. 3, the pressure of the toe 21 upon the follower tends to force the latter toward the lower wall of the spring socket, and the location of the stem of the attachment at the under side of the spring socket adapts it to serve as a guide or wear 90 element to prevent distorting the bore of the socket and prevent the catching of the follower on any unevenness of such wall as might be caused by friction. 95

What I claim is:—

As an article of manufacture, an attachment for standard loom-shuttles, the same being struck from flat pliable sheet metal and having terminal disks and a reduced soft connecting stem one of said disks being 105 adapted for arrangement in the path, to receive the impact, of the heel of a bobbin spindle head, and the other disk being adapted for arrangement at the bottom of the socket for the spindle actuating spring, 110 the stem being bendable in opposite directions to position and space the disks.

This specification signed and witnessed this seventeenth day of February A. D. 1917.

JOSEPH HENRY HEARNE.
